UNITED STATES PATENT OFFICE

WALTER F. PIPER, OF CHICAGO, ILLINOIS, ASSIGNOR TO THE BEARDSLEY & PIPER COMPANY, OF CHICAGO, ILLINOIS, A CORPORATION OF ILLINOIS

MACHINE FOR FILLING FLASKS FOR FOUNDRY

Application filed June 7, 1929. Serial No. 369,082.

The invention relates generally to foundry equipment. More particularly the invention relates to that type of equipment which includes a movably mounted projector for ramming sand into flasks.

One object of the invention is to provide an equipment of this type which is designed particularly for use in foundries wherein sufficient floor space is not available for a pile of sand from which the projector can be supplied.

Another object of the invention is to provide an equipment of the character hereunder consideration in which the projector is supported so that it can travel along a wall of the moulding room of the foundry and is adapted to receive sand continuously from an overhead conveyor.

A further object of the invention is the provision of improved means for supplying sand from the conveyor to the projector.

A still further object of the invention is the provision of an improved truck or carriage on which the projector is mounted.

Other objects of the invention and the various advantages and characteristics of the present equipment will be apparent from a consideration of the following detailed description.

The invention consists in the several novel features hereinafter set forth and more particularly defined by claims at the conclusion hereof.

In the drawings which accompany and form a part of this specification or disclosure and in which like numerals of reference denote corresponding parts throughout the several views: Fig. 1 is a side elevation of an equipment embodying the invention. Fig. 2 is a plan of the device for delivering sand from the overhead conveyor to the sand projector. Fig. 3 is a front elevation of the equipment. Fig. 4 is a transverse section taken on the line 4—4 of Fig. 3. Fig. 5 is a rear elevation of the sand feeding mechanism that is mounted on the truck. Fig. 6 is a horizontal section taken on the line 6—6 of Fig. 7. Fig. 7 is a rear-elevation of the lower portion of the truck.

The equipment which forms the subject

matter of this invention is adapted for use in a foundry and comprises a wheeled vertically extending frame or truck. The latter is built up of a pair of horizontal longitudinally extending channel beams 11 which are spaced apart, a pair of standards 10 which are formed of I-beams and have their lower ends secured to and positioned between the beams 11, and a pair of upper longitudinal channel beams 12 which are secured to and connect rigidly the upper ends of the standards 10. The beams 11 and 12 and the standards 10 are secured rigidly together so that the truck or frame is of a rigid character. A pair of supporting wheels 13 and 14 are arranged in tandem between beams 11 and are mounted on axles 15 which are journalled in and extend through the aforesaid beams. These wheels are adapted to run on a single rail 16 which is laid in or supported on or near the moulding room floor. The rail 16 is preferably positioned in close proximity to one of the side walls of the moulding room, so that the truck may travel longitudinally from one end of the moulding room to the other. Vertical axles 17 are fixedly secured to the outer sides of standards 10 respectively, adjacent their upper ends, and wheels 18 are journalled on said axles. The peripheries of said wheels are adapted to run on the inner face of a channel beam 19 which extends longitudinally from end to end of the moulding room, and serves as a thrust rail for maintaining the truck in a vertical plane. Beam 19 is secured by brackets 20 to overhanging bars 21 which are secured to columns 22. The latter are permanently supported in the moulding room adjacent a wall thereof. The truck is propelled longitudinally of the wall to bring the flasks within reach of a sand projector on the truck, by mechanism comprising an electric motor 23 and reduction gearing. The latter consists of a worm 25 which is mounted on the shaft of motor 23 and is housed in a case 24; a gear 26 which is driven by said worm; a sprocket-wheel 27 which is disposed at one side of case 24 and is driven by gear 26; a sprocket-chain 28 which is driven by sprocket-wheel 27; a

sprocket wheel 29 which is fixed to rotate the supporting wheel 13; a sprocket wheel 30 which is disposed at the other side of case 24 and, like the sprocket-wheel 27, is 5 driven by gear 26; a sprocket-chain 31 which is driven by sprocket wheel 30, and a sprocket-wheel 32 which is fixed to rotate supporting wheel 14. Motor 23 and gear-case 24 are mounted upon a bed or bracket 33 10 which is secured to one of the standards 10.

The said projector is mounted so that it is bodily movable with the truck and hence may be shifted to fill flasks throughout the 15 length of the moulding room floor. The supporting structure for the projector comprises a horizontal plate 34, plate metal brackets 35, a longitudinal angle bar 36 which extends between and is secured to the standards 10, a longitudinal reinforcing angle bar 37 20 which is located under plate 34, and reinforcing corner bars 38 between brackets 35 and plate 34. The projector comprises a casing 40 containing a high speed rotary projector-blade (not shown) for sling sand into subjacent flasks; an arm 41, on which casing 40 is fixed; an electric motor 42 for driving the blade, mounted on and movable with said arm; an endless belt 41^a mounted 25 on the arm and driven by said motor, for continuously supplying sand to the projector casing; a vertically swinging jib 43 pivoted at 44 to a horizontally rotatable sleeve 45, and composed of an inner member 46 and 30 an outer member 47 which is pivoted to the outer end of the inner member to permit relative vertical pivotal movement between the members in raising and lowering the casing 40 and arm 41; a post 48 fixed on plate 34 of the truck, and around which sleeve 45 35 is supported for horizontal rotation; an endless conveyor 49 for delivering sand from a hopper 51 into a chute 52 over belt 53 and supported by arm 41; and an electric motor 54 on jib member 43, for operating gearing 40 in a case 55, for raising and lowering the jib. Arm 41 is pivoted at 56 to swing horizontally relatively to the vertically adjustable jib member 47. The outer end of conveyor belt 49 is supported by arms 57 fixed 45 to a bracket 58 which is rigid with jib member 47, and the inner end of said belt is supported by a case 59 which contains gearing 50 for driving said belt. Rods 60^a, which are pivoted to a pivot-bracket 58 to which jib-member 47 is fixed, and to sleeve 45, constitute, with jib-member 43, a parallel linkage 55 for maintaining the horizontality of jib-member 47, arm 41 and the projector-head carried thereby. The construction and operation 60 of the mechanism for raising and lowering the projector and feeding sand thereto are fully set forth in an application for Letters Patent of the United States filed Feb. 13, 1926, Serial No. 88,014, and the construction and operation of the projector-head 65

are more fully set forth in Patent No. 1,667,097, to which reference may be had for a more detailed description thereof.

The equipment thus far described exemplifies a truck which is adapted to travel the 70 length of a moulding room and adjacent a wall of, or a series of fixed columns in, the room, and a projector which is mounted on the truck, and in which the projector-head is movable horizontally to sling sand into all 75 portions of subjacent flasks, and is adjustable vertically, so it can be positioned for filling flasks of different heights or to clear parts on the floor of the moulding room when the truck is moved lengthwise of the floor.

An overhead conveyor, for supplying the projector with sand throughout its travel from end to end of the moulding room, comprises an endless belt 60 which extends the 80 length of the room and around pulleys 61, 62, 85 one of which is continuously driven during the operation of the projector, by any suitable mechanism. This belt receives sand from any suitable source of supply, and its upper reach is intermediately supported by rollers 63, and its lower reach by rollers 64. The conveyor is supported by a structure which comprises longitudinal beams 65 which are fixed to beams or arms 21 which project outwardly from columns 22, and cross-bars 67 90 which are fixed to beams 65. Brackets 58 for carrying rollers 63 and brackets 70 for carrying rollers 64, are mounted on bars 67.

Mechanism for delivering sand from the belt 60 into a hopper 51 over the jib-member 100 43 comprises an inclined deflector or sweep 105 which is mounted to travel with the truck, and is adapted to discharge sand from the top reach of the belt to the front side thereof. A hopper 72, movable with the truck and sweep 71, is adapted to receive the sand as it is discharged from the belt 60 by the sweep 71. A deflector, for directing the sand discharged laterally from the belt 60 by sweep 71 into the hopper 72, comprises a vertical 110 wall 71^a and an inclined wall 71^b. This deflector is also supported to travel with hopper 72 and the sweep. Wings 71^c are provided to confine the sand discharged from belt 60 to the deflector 71^a, 71^b. The top reach of an 115 endless slat conveyor 73 underlies or forms the bottom of the hopper 72, and is carried by a driven pulley 75 and an idler pulley 74. This conveyor 73 discharges the sand 120 into the hopper 51 as it passes around pulley 75. A gate 76 is slidably mounted on the side of hopper 72 above conveyor 73 and pulley 75, to regulate the volume of sand discharged from the hopper 72 and delivered 125 into the hopper 51. Said gate is vertically slidable in guides 81, and a bolt 82, extending through a slot 83 in a bar 84 fixed to the gate, is adapted to secure the gate in its assigned position by raising and lowering the gate. The gap under the lower end of the gate may 130

be varied to vary correspondingly the volume of sand delivered to the projector. Conveyor 73 is continuously driven by mechanism comprising an electric motor 77 and enclosed 5 worm gear reduction 78, a pinion 79 driven by said reduction, and a gear 80 fixed to the shaft of pulley 75. The mechanism for delivering sand from belt 60 into hopper 52 of the projector is supported on the truck by a 10 structure comprising a pair of channel beams 86 which are fixed to the standards 10 and project forwardly therefrom; a pair of longitudinal beams 87 fixedly secured on top of beams 86; and angle bars 88 fixed to beams 15 87, to which the front and back of the hopper 72 are fixedly secured. Pulley 75 is journaled in bearings 75^a fixed to beams 87, and pulley 74 is mounted in bearings 74^a which are slidably adjustable in ways 74^b to permit 20 the conveyor 73 to be tightened. The deflector 71^a, 71^b is supported from the hopper by brackets 89, the lower ends of which are fixed to the sides of said hopper. The sweep 71 is 25 pivotally supported at 90 in the upper ends of brackets 89, and is provided with a forwardly projecting arm 91, to which a cord 92 is attached so that the sweep may be lifted off the belt 60 to discontinue the discharge of sand from the belt when desired. An angle 30 iron bar 93 cross connects the upper ends of brackets 89. This exemplifies mechanism which is movable longitudinally with the truck, for discharging sand from the supply belt into a hopper from which the sand 35 is fed in regulated quantity to the projector.

In some instances, it is desired to utilize the truck to transport flasks or in inverting them to place the mates together, preparatory to pouring the metal into the moulds. For 40 this purpose, a crane is mounted on one of the standards 10, so that it will travel with the truck. This crane comprises a boom 95 of channel iron, on which a wheeled hoisting device 97 is adapted to travel, and a mast 98, 45 to which the boom is fixedly secured. The mast 98 is pivotally connected by bolts 99 to one of the standards 10 of the truck. Bolts 99 extend through pivot lugs 100 which are fixed to the mast 98 and through brackets 101 which 50 are fixed to the front of column 10. The boom may be swung horizontally to bring the hoisting device 97 over the load to be handled.

The operation of the equipment will be as follows: Supply belt 60 will be continuously 55 operated to deliver sand from the source of supply, and since it extends throughout the length of the moulding room, it provides an available supply to the projector throughout its range of travel between the ends of the 60 room. The sweep 71 discharges the sand laterally from belt 60 against deflector 71^a, so the sand will be discharged downwardly into the hopper 72. The sweep, being movable over the belt 60, is adapted to effect this discharge in all positions of the truck. The

hopper 72 is adapted to contain a sufficient supply of sand to keep the projector machine supplied, despite any variations in the delivery of the sand by the belt 60 and sweep 71 during the movements of the truck, such as 70 may occur when the truck is being driven toward or from the delivery end of feed belt 60. From hopper 72, the sand is discharged in regulated quantity under control of gate 76, 75 into the hopper 51, from which the sand is delivered into the projector head by belt 49 on the jib and belt 41^a on the arm. The vertical axis, about which the jib swings, is disposed below the point of discharge of the sand from conveyor 73, so that the jib may be 80 manually shifted from the side without interrupting the sand feed. The pivotal connections for the jib 43 and the arm 41 permit the projector-head to be moved horizontally so that the sand will be projected at a high rate of speed directly into all portions of the flasks, and the jib may be adjusted to raise or lower the projector head, as more fully set forth in the aforesaid application No. 88,014 filed Feb. 13, 1926. The truck, during the 85 operation of the projector, may be propelled by motor 23, so that the machine will move lengthwise of the moulding room, and between flasks without interrupting the projection of sand into the flasks and without interrupting the sand delivery from the overhead sand supply belt 60 to the projector.

The invention exemplifies an equipment which may be supported along the wall of a moulding room or a series of columns therein 90 and thereby leaves the maximum space available on the moulding room floor for filling the flasks for moulding; also an equipment including a sand projector, to which the sand is continuously supplied from an overhead sand conveyor.

The invention is not to be understood as restricted to the details set forth, since these may be modified within the scope of the appended claims, without departing from the 100 spirit and scope of the invention.

Having thus described the invention, what I claim as new and desire to secure by Letters Patent, is:

1. In foundry equipment, the combination 115 of a truck, a rail on which the truck is adapted to travel across a moulding room, overhead guide-means for holding the truck against lateral displacement, a moulding machine mounted on and projecting from the truck and adapted to fill flasks on the floor of the room, an overhead sand supply supported independently of the truck and extending through the traverse of said truck, and mechanism mounted on the truck for delivering sand from the overhead supply to the moulding machine.

2. In foundry equipment, the combination 120 of a truck, a rail on which the truck is adapted to travel across a moulding room, overhead

guide means for holding the carriage against lateral displacement, a moulding machine mounted on and projecting from the truck and adapted to fill flasks on the floor of the room, mechanism for propelling the truck comprising a motor mounted on the latter, an overhead sand supply supported independently of the truck and extending throughout the traverse of said truck, and mechanism mounted on the truck for delivering sand from the overhead supply to the moulding machine.

3. In foundry equipment, the combination of a truck comprising a vertically extending frame, a single rail on which the truck is adapted to travel across a moulding room, overhead guide-means for the upper end of the frame adapted to hold the truck against displacement, a moulding machine mounted on the truck and projecting therefrom, an overhead sand supply supported independently of the truck and extending throughout the traverse of said truck, and mechanism mounted on the truck for delivering sand from the overhead supply to the moulding machine.

4. In foundry equipment, the combination of a truck comprising a vertically extending frame and a pair of wheels in tandem, a single rail on which the wheels travel, an overhead rail for guiding the upper end of the frame, a moulding machine mounted on the truck and projecting therefrom, an overhead sand supply supported independently of the truck and extending through the traverse of said truck, and mechanism mounted on the truck for delivering sand from the overhead supply to the moulding machine.

5. In foundry equipment, the combination of a truck comprising a pair of longitudinal beams, supporting wheels arranged in tandem between said beams, standards secured to said beams, and lateral thrust wheels at the upper ends of the standards, a floor rail on which the supporting wheels travel, an overhead rail on which the thrust wheels ride, a moulding machine mounted on the truck, an overhead sand supply supported independently of the truck and extending through the traverse of said truck, and mechanism mounted on the truck for delivering sand from the overhead supply to the moulding machine.

6. In foundry equipment, the combination of a truck, a rail on which the truck is adapted to travel along a moulding room, overhead means for guiding the truck against displacement laterally, a moulding machine mounted on the truck and comprising a rotary sand projector movable horizontally relatively to the truck to fill all portions of flasks on the floor of the room, an overhead sand supply supported independently of the truck and extending throughout the traverse of said truck, and mechanism mounted on the truck

for delivering sand from the overhead supply to the projector.

7. In foundry equipment, the combination of a truck adapted to travel along a moulding room, a rail for said truck, a stationary overhead track for guiding the truck laterally, a moulding machine mounted on the truck and projecting from one side of the truck to fill flasks on the floor of the room, an overhead sand supply supported independently of the truck and extending throughout the traverse of said truck, and mechanism mounted on the truck for delivering sand from an overhead supply to the moulding machine.

8. In foundry equipment, the combination of a truck adapted to travel along a moulding room, a rail for said truck, a stationary overhead thrust track for guiding the truck laterally, a moulding machine mounted on the truck and comprising a rotary sand projector extending outwardly and adapted to fill flasks on the floor of the room, an overhead sand supply supported independently of the truck and extending throughout the traverse of said truck, and mechanism mounted on the truck for delivering sand from the overhead supply to the projector.

9. In foundry equipment, the combination of an overhead belt for conveying a supply of sand over a moulding room, a vertically extending truck adapted to travel in the moulding room longitudinally of the belt, overhead means for guiding the truck laterally, a moulding machine mounted on the truck and projecting therefrom to fill flasks on the floor of the room, and means for delivering sand from the belt to the moulding machine throughout the traverse of the truck.

10. In foundry equipment, the combination of an overhead belt for conveying a supply of sand over a moulding room, a vertically extending truck adapted to travel on a rail in the room and longitudinally of the belt, overhead means for guiding the truck laterally, a moulding machine mounted on the truck and comprising a rotary sand projector movable relatively to the truck, and means for delivering sand from the belt to the projector throughout the traverse of the truck.

11. In foundry equipment, the combination of an endless overhead conveyor mounted to supply sand over a moulding room, a vertically extending truck adapted to travel on a rail and longitudinally of the conveyor, a moulding machine mounted on and movable with the truck, and mechanism movable with the truck for delivering sand from the conveyor to the moulding machine throughout the traverse of the truck, comprising a sweep to discharge the sand from said conveyor.

12. In foundry equipment, the combination of an endless overhead conveyor mounted to supply sand over a moulding room, a ver-

5 tically extending truck adapted to travel on a rail and longitudinally of the conveyor, a moulding machine mounted on and movable with the truck, and mechanism movable with the truck for delivering sand from the conveyor to the moulding machine throughout the traverse of the carriage, comprising a sweep, movable into and out of position to discharge sand from the conveyor.

10 13. In foundry equipment, the combination of a truck adapted to travel on a rail along a moulding room, a moulding machine comprising a rotary sand projector mounted on the truck so it may be moved horizontally relatively thereto, an overhead sand conveyor supported independently of the truck and extended throughout the traverse of the truck, and mechanism mounted on the truck for delivering sand from the conveyor to the projector, comprising a sweep to discharge the sand from said conveyor.

15 14. In foundry equipment, the combination of a truck adapted to travel on a rail along a moulding room, a moulding machine comprising a rotary sand projector mounted on the truck so it may be moved horizontally relatively to the truck, an overhead sand conveyor supported independently of the truck and extending throughout the traverse of the truck, and mechanism mounted on the truck for delivering sand from the conveyor to the projector, comprising a sweep to discharge the sand from said conveyor, and a hopper positioned under and adapted to receive the sand from the sweep.

20 15. In foundry equipment, the combination of a truck adapted to travel along a moulding room, a moulding machine comprising a rotary sand projector mounted on the truck so it may be moved horizontally relatively to the truck, an overhead sand conveyor supported independently of the truck and extending throughout the traverse of the truck, means for discharging sand from the conveyor, and an endless conveyor mounted on the truck and adapted to receive sand from the discharging means and to deliver it to the moulding machine.

25 16. In foundry equipment, the combination of a truck adapted to travel along a moulding room, a moulding machine comprising a rotary sand projector mounted on the truck so it may be moved horizontally relatively thereto, an overhead sand conveyor supported independently of the truck and extending throughout the traverse of said truck, means for discharging sand from the conveyor, and controllable means mounted on the truck, for delivering the sand from the discharge means to the moulding machine.

30 17. In foundry equipment, the combination of a truck adapted to travel along a moulding room, a moulding machine comprising a rotary sand projector mounted on the truck so it may be moved horizontally relatively

thereto, an overhead sand conveyor supported independently of the truck and extending throughout the traverse of the truck, means for discharging sand from the conveyor, and means for delivering the sand from the discharge means to the projector comprising a hopper fixed on the truck, and an endless belt beneath the hopper.

35 18. In foundry equipment, the combination of a truck adapted to travel along a moulding room, a moulding machine comprising a rotary sand projector mounted on the truck so it may be moved horizontally relatively thereto, an overhead sand conveyor supported independently of the truck and extending throughout the traverse of the truck, means for discharging sand from the conveyor, a hopper mounted on the truck beneath the conveyor, a deflector to direct the sand discharged from the conveyor to the hopper, and an endless belt mounted on the truck under the hopper, for delivering sand from the hopper to the projector.

40 Signed at Chicago, Illinois, this 19th day of October, 1928.
